SHIPPING CONTAINER

James J. Deegan, Downers Grove, Ill., assignor to Inland Steel Company, Chicago, Ill., a corporation of Delaware

Filed July 3, 1963, Ser. No. 75,656

Term of patent 14 years

(Cl. D58—11)

FIGURE 1 is a side elevational view of a shipping container embodying my new design.

FIGURE 2 is a fragmentary vertical section on an enlarged scale of the side wall of the shipping container shown in FIGURE 1.

FIGURE 3 is a top plan view on a reduced scale and in dotted line form showing the outline of the shipping container shown in FIG. 1.

The essential feature of my design resides in the portions of the drawing shown in full lines.

The design for the shipping container is characterized by the provision of a repeating pattern of alternate beads having convex cross-sections and furrows wherein in the axial extent of each bead exceeds the axial extent of each furrow.

I claim:
The ornamental design for a shipping container, substantially as shown and described.
